UNITED STATES PATENT OFFICE.

ALFRED PARR, OF LONDON, ENGLAND.

MACHINE FOR LABELING BOTTLES, BOXES, PACKETS, AND SIMILAR ARTICLES.

Application filed February 11, 1925, Serial No. 8,503, and in Great Britain February 22, 1924.

- This invention relates to a machine for applying labels to boxes, bottles, packets and other receptacles, and of that kind in which the boxes or other receptacles are conveyed by a band or traveller between two label applying devices, one on each side, and which pick up the labels and alternately apply same to the boxes, etc., said labels having an adhesive applied to them before they are presented to the boxes.
- 5 My improved machine has the distinguishing feature that the label carriers or label applying devices are of that kind in which the labels are lifted from piles by suction and are so held until applied to the boxes or other receptacles when the suction or vacuum is broken.
- 10 Each label carrier is designed to take up and apply one label at a time, but groups of label carriers may be employed adapted either for the application of two or more labels to one article, as, for example, two body labels and one neck label to a bottle, or two or more single labels to a like number of separate articles.
- 15 The label carriers are mounted on a slideable body adapted to move to and fro in a guide or frame disposed transversely over the conveyor, or track, on or along which the articles to be labeled are carried, and the said guide or frame is so mounted that it may be raised and lowered so that the label carriers may be brought into contact with the label piles at one end of their travel and into contact with the articles to be labeled at the other end of their travel in the said guide or frame, and that they may be lifted out of contact with same when moving horizontally to and fro.
- 20 After application of the label, or labels, to an article, or articles, carried in or on the conveying mechanism the said conveying mechanism is moved forward a stage, so as to bring the labeled articles under pressing mechanism, or devices, and another article, or group of articles into position for labeling.
- 25 The pasting devices are carried on tables which are so mounted that they may be raised by means of levers actuated by suction devices connected with the same suction main as are the label carriers. The rise of the said table will be such as will bring the surface of the pasting rollers into contact with the under surfaces of the labels which are carried over them while pneumatically attached to the label carriers. It will be obvious that excepting when a label is in pneumatic attachment with the face of the label carrier, no vacuum will be formed either in the label carrier or in the suction device for lifting the tables supporting the pasting devices, and consequently the pasting roller will never be brought into contact with the bare face of a label carrier.
- 30 An example of my machine is shown in the accompanying drawings in which a machine having two groups of label carriers, each comprising three members, is shown.
- 35 Fig. 1 is a front elevation of the machine.
- 40 Fig. 2 is a back view of the same machine.
- 45 Fig. 3 is a top or plan view, and
- 50 Fig. 4 is an end view.
- 55 Fig. 5 is a plan of cam movements employed in the machine.
- 60 Fig. 6 shows the suction device for raising the gum tanks.
- 65 Fig. 7 shows a detail in side elevation.
- 70 Fig. 8 shows a free wheel ratchet mechanism, the position of which is indicated by dotted lines in Fig. 7.
- 75 Fig. 9 is an elevation showing the reciprocating slide.
- 80 Fig. 10 is an end view of the same.
- 85 Fig. 11 is an enlarged transverse section on line 11—11 of Fig. 9.
- 90 Fig. 12 is an enlarged broken elevation showing the slide in cooperative relation with the frame and vacuum pump tube.
- 95 Fig. 13 is a rear elevation showing the connection of one of the vacuum pumps.
- 100 Fig. 14 is a similar view showing the mounting of the other vacuum pump.
- 105 Fig. 15 is a view of another detail.
- 110 The machine shown comprises main frame 1, to the lower part of which a shaft 2 is driven from toothed wheels 3 and 4 is fitted. The wheel 4 is driven in any convenient manner from a motor.
- The label carriers *a a a* and *b b b* are mounted on a slide 5 by means of hollow stems, 5', the slide being adapted to reciprocate horizontally in a frame 6 to which vertical rising and falling movement is imparted.
- Gumming rollers are shown at 7, 7 and piles of labels at *c c c* and *d d d*. A centrally arranged endless conveyor or track is formed of the chains 8 and presses for the labels are seen at 9. These may be of the kind described in the specification of my and another's British Patent 17,398, of 1914, more

particularly with reference to Fig. 18 therein. The conveyor runs over sprocket wheels 10.

It will be understood that the faces of the 5 label carriers, the label holders and the gumming rollers are all of appropriate relative sizes, and that they are all exchangeable for others of another size or shape, so that the machine can be adapted to apply labels 10 of various sizes to corresponding boxes or other receptacles.

A vacuum pump 11 is connected by tube 12 through one end of the slide 5 and to the label carriers *a a a*. A like pump 13 is connected by tube 14 to the opposite end of the 15 slide 5 to the label carriers *b b b*. The pump 11 has a branch pipe 15 connected to barrel 16 in which is a plunger 17. This plunger is connected to a lever 17^a which lifts a rod 20 17^b on which is a plate 17^c carrying the paste reservoir 7 for the labels on carriers *a a a* and a like branch pipe 18 from pump 13 is connected to a similar barrel with a plunger and lever (not shown) for the carriers *b b b*. 25 The shaft 17^d on which the lever 17^a is mounted carries a second short lifting lever for another rod equivalent to 17^b and attached to the other end of the plate 17^c. Two rods are employed to ensure smooth up 30 and down movement. The connections of these pipes are such that when a vacuum is created in the cylinders 11 and 13 the plungers are drawn into their barrels, and through their levers raise the paste pots and 35 their rollers into positions to contact with labels on the carriers; only the slight movement necessary to effect clearance is required.

It will be evident that if the air ports on 40 the faces of the carrier are not sealed by labels a vacuum cannot be created, and the plunger will be in operative and the paste rollers will not be raised.

The barrel of the vacuum pump 11 is carried 45 on a lever 19 pivoted at 19^a and actuated by a cam shown at 19^b on shaft 2 in Fig. 5. A like lever 21 pivoted at 20 and operated by cam 20^a is employed for the barrel of the pump 13. The pumps are thus operated 50 by moving their cylinders or barrels, the pistons remaining fixed. The operations of the pumps are alternate.

The frame 6 is carried on two brackets 22, 22 attached to vertical rods 23, 23 55 slidably mounted in fixed brackets 24, 24. The lower ends of these rods are raised and lowered by levers operated from cams 23^a on the shaft 2.

A pin 25 projects downwardly from the 60 slide 5 and is engaged by a slotted lever 26 mounted on a vertical rod 27 mounted in brackets 28, 29 on the frame 1. A short slotted lever 27^c projects from the lower end 65 of the rod 27 and is engaged by another lever 27^d actuated from the cam groove 27^a

in barrel 27^b in such a manner that the rod 27 is given a rocking or turning motion and which is converted into a sliding motion of the carrier 5 through the slotted lever 26. It is necessary for the rods 27 and 23 to rise 70 and fall together, and for that purpose I provide a yoke 30 on the rod 23 and a collar 31 on the rod 27 so that the said yoke will lift the rod 27 when the rod 23 rises.

As previously stated, the pump 11 is to be 75 connected to the label carriers *a a a* while the pump 13 is connected by the tube 14 to the label carriers *b b b*. The respective tubes 12 and 14 communicate with the slide by means of pipes 32 and 34. These respective pipes enter independent longitudinal openings in the ends of the slide, each of which openings 60 is of a diameter at its entrance end to just slidably receive the respective pipes, as indicated at 61 in Fig. 12. Inwardly of the portion 61, the openings 60 are diametrically enlarged, as at 62, to provide a space 63 which surrounds the particular pipe 32 or 34 when the slide has been moved to cause the end of the pipe to enter the enlargement. The enlarged portion 63 of the opening 60 communicates through a port 64 with a chamber 65 in an offset 66 of the slide 5, and the hollow stems 5' leading to the respective carriers *a* and *b* are in open communication with the respective chambers 65. The pipes 32 and 34 are formed with slots 67 which, when the slide 5 has been moved to a position to arrange the slots 67 in the restricted portion 61 of the opening 60, communication between the pumps and the carriers is obviously cut off. When the slide is moved to the opposite direction, communication is had between the pump and carriers to break the vacuum which holds 100 the labels to the carriers.

A like arrangement through tube 34 connects the pipe 14 with the carriers *b b b*.

The machine shown is of a type in which 110 the articles are carried by a conveyor under the label carriers and passed round and discharged at a lower level. The articles are seen at *x x x* and may, for example, be three cylindrical tins. These are passed on to the conveyor in any convenient manner and take up their positions in front of three pushers 35 held together by a plate 36 and mounted on a cross bar 37, the ends of which are engaged by a pair of levers 38, to which a short rocking movement is given by a lever 39 fixed to a shaft 40 on which the levers 38 are also fixedly mounted, see Fig. 15. The lever 39 is rocked from a grooved cam in the wheel 41 on shaft 2 and supported by a fork 42 resting over the shaft 2.

The chains 8 of the conveyor have intermittent movement imparted to them by a rack 43 engaging pinion 44 of the sprocket wheel 10. The rack 43, see Fig. 7, is connected to a bell crank lever 45, one arm of 120

which is rocked from a cam 47 on the shaft 2. Pawl and ratchet mechanism, Fig. 8, is provided between the pinion 44 and the sprocket 10 to prevent return rotation.

5 When the articles $\alpha \alpha \alpha$ are placed in the conveyor the blocks 35 are pushed forward and align the articles between clamping plates or their equivalents which will vary in design according to the tins, boxes or

10 other articles to be labeled.

The chains 8 are shown with clamping discs 46 between which the articles are held, and are carried forward from the pushers 35 to the label carriers and from the carriers to the presses and over the end of the conveyor. These discs are suitable for the cylindrical tins before mentioned, but would be exchanged for other kinds or devices for other articles.

15 20 For the purpose of rotating the gumming rollers 7, I provide a bevel wheel 50 on shaft 2 in mesh with a bevel pinion 51 which rotates two spur wheels 52 adapted to drive chains 53 which drive other wheels at 54 over which light chains or bands (not shown) run and drive the spindles of the said rollers.

Any suitable means for holding the labels and feeding the label tables upward may 25 be employed. In the drawings I have shown guides 55 with projections 56 adapted to engage the top of the pile of labels and prevent the pile rising beyond a predetermined level. When a label carrier comes down on 30 to the pile of labels it depresses the pile and the label holder is temporarily retained, during which the carrier rises and draws the label attached to it past the projection 56. Levers 57 are provided to release the label 35 carriers after depression, but are not described in detail as the method of storing the labels and manipulating the label holding mechanism may be as desired and forms no part of the present invention.

40 45 What I claim is:

1. A label applying machine, including separate label carriers, suction means cooperating therewith to hold the labels on the

carriers by suction, and means to operate said label carriers in alternate sequence for 50 applying the labels to successively presented articles, the respective label carriers being arranged in groups of two or more and operated to apply a plurality of labels to a single article.

55 2. In a label applying machine, two separate label carriers, suction means cooperating therewith to hold the labels on the carriers by suction, means to operate said label carriers in alternate sequence to apply the 60 labels to successively presented articles, a pasting device for the labels, and means for operating the pasting device controlled by the suction means for the label carriers.

3. In a machine for applying labels to 65 boxes or like receptacles, two label carriers mounted for simultaneous horizontal and simultaneous vertical movement, means for introducing such movements in the label carriers, and suction means operating 70 through the label carriers to pick up labels and apply such labels to successively presented receptacles.

4. In a label applying machine two separate label carriers, suction means cooperating therewith to hold the labels on the carriers by suction, means to operate the label carriers, a pasting device including a paste receptacle and a paste applying roller operating therein, a rod for elevating the paste 75 receptacle, and means controlled by the suction means for operating the rod.

5. In a label applying machine two separate label carriers, suction means cooperating therewith to hold the labels on the carriers by suction, means to operate the label carriers, a pasting device including a paste receptacle, and a paste applying roller operating therein, a rod for elevating the paste 80 receptacle, a barrel connected to said suction means, a plunger in the barrel, and means actuated by the plunger for actuating the rod to lift the pasting device.

85 90 In testimony whereof I affix my signature.

ALFRED PARR.
